G. T. MCLEOD.
SHOEMAKER'S WORK BENCH.
APPLICATION FILED OCT. 27, 1909.

1,104,372.

Patented July 21, 1914.

UNITED STATES PATENT OFFICE.

GEORGE T. MCLEOD, OF DEDHAM, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

SHOEMAKER'S WORK-BENCH.

1,104,372.

Specification of Letters Patent. Patented July 21, 1914.

Application filed October 27, 1909. Serial No. 524,952.

To all whom it may concern:

Be it known that I, GEORGE T. MCLEOD, a citizen of the United States, residing at Dedham, in the county of Norfolk and State of Massachusetts, have invented an Improvement in Shoemakers' Work-Benches, of which the following description, in connection with the accompanying drawings, is a specification, like letters on the drawings representing like parts.

The invention to be hereinafter described relates to shoemakers' work benches and more particularly to such work benches as used by operators in assembling the upper and last and lasting the shoe.

As well understood by those skilled in the art it is usual, in the manufacture of boots and shoes, to assemble the upper and lining on the last, then place the assembled parts on a bench from which they are taken by the lasters, who pull over the upper, and tack it to the last. As heretofore constructed these work benches have not been suitable for the work, and moreover when placed upon the bench after assembling the loose tacks thereon have been the cause of much injury to the shoe upper.

The aims and purposes of the present invention are to provide a shoemaker's work bench of simple construction which will be adapted to the needs of the assemblers and lasters and wherein the two operators' and main benches are so related and disposed with reference to each other that as the shoe parts and last are assembled and laid upon the main work bench, they will be convenient to the laster who next takes them, and wherein the upper will not become injured by loose tacks lying on the bench.

Other objects and purposes of the invention will appear from the description and accompanying drawings of one form of the present invention.

In the drawings: Figure 1 is an isometric view of a shoemaker's work bench constructed in accordance with the present invention; and Fig. 2 is a detail in cross section on the line 2-2, Fig. 1.

The work bench, as a whole, comprises a main work bench, an assembling bench and a lasting bench, said benches being formed of metal, and so relatively disposed that as a shoe and last are assembled at the assem-

bling bench and laid upon the main work bench, they are convenient to the laster at work at the lasting bench.

In the drawing the main work bench comprises a top 1 of desired size having an unobstructed upper surface, and preferably formed of a metal plate having slots or openings 2 therethrough. These slots or openings 2 extend longitudinally of the bench top 1 and are of a size to readily permit any loose tacks or other articles liable to injure the shoe upper to pass through, while the bench top may afford an unobstructed support for assembled or lasted shoes placed thereon. It will be noted that the bench top is formed of a metal plate 70 which may be cast or otherwise formed with elongated openings 2, said openings being of less length than the dimension of the top plate in the same direction, whereby there is formed between the end portions of 75 the openings a series of webs integral with the top plate and serving to impart thereto the necessary rigidity of structure, while providing an unobstructed perforated support for the shoes placed thereon that the uppers may not receive injury from loose tacks which might otherwise lodge on the top plate. In other words, the top plate, while having the elongated openings for the free passage of tacks and other foreign substances, is connected and joined together throughout by web portions extending between the ends of the elongated openings forming an integral and rigid support.

Around the rear and end portions of the 90 bench top is a metal flange 3, the front edge of the metal top 1 being downturned, as at 4, to provide a flange against the inner surface of which rests the side of the metal legs 5. The legs 5 at their top portion are 95 bent or turned over, as at 6, and a rivet, screw, or other fastener 7 passes through the bench top 1 into the turned over end of the leg top to secure the legs and top together. The rear legs 8 may be similarly joined to 100 the bench top, and the front and rear legs are joined together by the ties or pieces 9 and 10. As one convenient way of forming the legs 5, 8 and their joining pieces, they may be cast as one piece of metal, if desired, 105 though this is not essential. Extending in front of the main work bench is the assembling bench 11, which, like the main work

bench, has the top 12 formed of metal and provided with a series of elongated slots 13. The assembling bench is likewise formed with an upwardly projecting flange 14 extending around the four edges thereof.

It will be noted that the assembling bench 11 is lower than the top of the main work bench to provide the proper height of bench suitable to the assembling operation, said 10 assembling bench preferably extending between two legs 5, 5 of the main work bench to which it is secured by suitable fasteners and braced by bracket arms 15. At its outer edge portion the assembling bench is provided with a boss 16 having a vertical opening for the passage of an assembling spindle 17 which rises from a base support 18, and has at its top a pin 19 to engage the last pin socket of a last, while permitting 15 the last to be swung and turned around on said pin in a manner suitable to the assembling operation. Secured to the front of the main work bench, adjacent to but separated from the assembling bench, is the lasting bench 20 formed of a metal plate 21 having the slots or openings 23 and the flange 22, said lasting bench being secured to the main bench on a level with the top thereof as is 20 most suitable to the work of lasting the shoe. 25

30 Suitable bracket arms 24 may be employed to strengthen the support of the lasting bench. The assembling and the lasting benches, like the main bench, have the elongated openings 13 and 23 respectively of less 35 length than the dimension of the respective benches in the same direction, whereby there are formed a series of integral web portions between the ends of the elongated openings which tie the metal plates together at intervals forming a rigid yet open supporting 40 surface.

From the construction thus far described it will be apparent that as the uppers and lasts are assembled on the assembling spindle 17, said parts being taken from the assembling bench, they are laid in convenient position on the main work bench from which they may be taken as desired by the operator stationed at the lasting bench, who pulls 45 over the upper and drives the desired number of tacks therethrough and into the last. Owing to the fact that the main work bench and the assembling and lasting benches are formed of metal and provided with the slots 50 or openings, as described, it will be apparent that shoes resting on any of these parts will not become injured by contact with sharp substances, such as tacks, or, indeed, splinters of wood or other objectionable matter. 55 Moreover the disposed relation of the main work bench, the assembling work bench and the lasting work bench is such as to enable the operators to successively assemble and last the shoe in convenient and expeditious manner, the height of the assem-

bling bench being made suitable with relation to the main work bench to the work to be performed, and the lasting bench being disposed at a height convenient for the laster.

At the front portion of the lasting bench 20 there is a boss 25, Fig. 2, having an aperture formed therein through which passes the spindle 26 rising from a base 27. Extending longitudinally of the spindle 26 is 70 the lasting board 28 having secured thereto by suitable screws 29 or otherwise the jack supporting head 30. The jack supporting head has a central stud 31 provided with a wing nut 32, and between the flanged portions of the head 30 and upon the stud 31 is mounted the arm 33 of the jack. This arm 33 carries bearing portions 34 for the jack spindle 35 on which is suitably mounted the hinged piece 36 carrying the pin 37 and the toe rest 38, the construction being such that the pin 37 may be caused to be engaged with the pin socket of the last on which the upper has been placed, and the toe rest 38 may be caused to engage beneath the toe of the assembled last and upper in convenient position to enable the laster to properly pull over the upper and drive the lasting tacks, as will be understood by those skilled in the art.

The lasting board 28 has secured thereto at its rear portion a strap 39, Fig. 2, said strap having a bent central portion 40, as indicated in Fig. 2, to pass about the spindle 26 adjacent the boss 25 of the lasting bench. The strap 39 is secured to the lasting board 28 and clamped to the spindle 26 by means of suitable bolts 41, the construction being such that the operator standing at the lasting bench may adjust the board 28, 100 and perform the jack, into desired position for the performance of the lasting operation, and may manipulate the jack to facilitate the further detailed positioning of the shoe upper, as by turning the shoe bodily 105 with the jack about the axis of the jack spindle 35. In order that the jack may be held in desired position when swung about with the spindle 26, suitable to the particular operator, a set screw 42, Fig. 2, is provided 110 which passes through the boss 25 and binds against the post 26 at its upper portion.

It is desirable that a main work bench and an assembling and lasting work bench be disposed with relation to each other, as 115 indicated in Fig. 1, so that the operators may conveniently and expeditiously act upon a series of shoes in the performance of their respective functions, each of said benches being so related with respect to each other that the operators at each may have his particular bench suited to the particular operation performed by him.

What is claimed is:

1. A shoemaker's work bench comprising 120

10 a main work bench, and an assembler's bench and a laster's bench secured to and projecting from the main work bench, each of said benches having a metal top plate provided with elongated openings of less length than the respective benches in the same direction and forming between the ends of such elongated openings web portions integral with the top plate of the respective 15 benches.

15 2. A shoemaker's work bench comprising a main work bench, and an assembler's bench and a laster's bench secured to and projecting from the main work bench, each of said benches having a metal top plate provided with elongated openings of less length than the respective benches in the same direction and forming between the ends of such elongated openings web portions integral 20 with the top plate of the respective benches, the main work bench being of a length greater than the combined lengths of the assembling and lasting benches.

25 3. A shoemaker's work bench having a supporting surface comprising a rigid metallic plate, said plate being provided with a plurality of series of openings for the passage of tacks and having integral portions separating adjacent openings.

30 4. A shoemaker's work bench formed of metal and comprising a main work bench, an assembling work bench located at one end of the main work bench and projecting from the front of the main work bench at a lower

level than the top thereof and having an 35 assembling spindle, and a lasting bench at the other end of said main work bench and also projecting from the front of the main work bench at the level thereof and provided with a lasting jack, the main work 40 bench having an unobstructed surface extending between the assembling and lasting benches, the tops of said benches being perforated for the passage of tacks.

45 5. A shoemaker's work bench comprising a main work bench, and an assembling work bench at one end thereof and a lasting bench at the other end thereof, said main work bench having a metal top plate provided with elongated openings for the passage of 50 tacks, said elongated openings being of less length than the dimension of the top plate of the main work bench in the same direction and having their adjacent ends separated by web portions integral with the top 55 plate of the main work bench.

6. A shoemaker's work bench having a perforated boss 25, a spindle 26 sustained upon the floor and passing through said boss, a board 28 carrying a jack, and a clamp 39 60 for clamping the board and spindle together.

In testimony whereof, I have signed my name to this specification, in the presence of two subscribing witnesses.

GEORGE T. MCLEOD.
